UNITED STATES PATENT OFFICE.

GABRIEL MURLASITS, OF LYNDORA, PENNSYLVANIA.

RAIL-JOINT.

No. 831,292.

Specification of Letters Patent.

Patented Sept. 18, 1906.

Application filed June 30, 1906. Serial No. 324,168.

To all whom it may concern:

Be it known that I, GABRIEL MURLASITS, a subject of the Emperor of Austria-Hungary, residing at Lyndora, in the county of Allegheny and State of Pennsylvania, have invented certain new and useful Improvements in Rail-Joints, of which the following is a specification, reference being had therein to the accompanying drawings.

This invention relates to certain new and useful improvements in rail-joints; and the invention has for its object to provide novel means for firmly holding the confronting ends of two sections of rails, whereby they cannot be displaced by rolling-stock passing over the same.

The invention aims to dispense with the nuts and bolts heretofore used in connection with rail-joints, and to provide positive means for supporting the ends of rails between two ties or sleepers. To this end I have devised a novel chair and fish-bar which are particularly designed to firmly hold the confronting ends of two rails and prevent said rails from spreading, at the same time permitting of expansion and contraction of said rails.

The detail construction of my improved joint will be presently described and specifically pointed out in the appended claims.

Referring to the drawings forming part of this specification, like numerals of reference designate corresponding parts throughout the several views, in which—

35. Figure 1 is a cross-sectional view of a track equipped with my improved joints. Fig. 2 is a perspective view of a joint. Fig. 3 is a cross-sectional view taken on line xx of Fig. 2. Fig. 4 is a similar view taken on line yy of 40 Fig. 2. Fig. 5 is a perspective view of my improved chair; and Fig. 6 is a similar view of a fish-bar used with the chair, the bar being illustrated as partially inverted.

To put my invention into practice, I construct my improved joint of a chair 1 and a detachable fish-bar 2, said bar being adapted to firmly hold the ends of two rails 3 and 4 upon the chair 1.

The chair 1 comprises a base-plate 5, carrying at its one edge a reinforced fish-bar 6, said bar having a flange 7 adapted to brace the outer sides of the heads 8 of the rails 3 and 4. The inner side of the fish-bar 6 is recessed, as at 9, and provided with a plurality of recesses or pockets 10, the object of which will be hereinafter described. The base-plate 5

at its opposite edge and adjacent to its ends is provided with spike-openings 11, through which spikes pass to secure said chair, rails, and fish-bar 2 to ties or sleepers 12. 60

The rails 3 and 4 are adapted to rest upon the chair and against the fish-bar 6 thereof. The rails are held by spikes 14, which are driven through the innermost openings 11 of the base-plate 5. To prevent longitudinal 65 movement of said rails, the web portions 15 thereof are provided with openings 16, and in said openings are mounted pins 17, which enter the recesses or pockets 10 of the fish-bar 6. These pins, in conjunction with the fish-bar 2, 70 which will now be described, serve to prevent longitudinal movement of said rails.

The fish-bar 2 is adapted to seat upon the chair 1 and embrace the rails 3 and 4. The inner side of the fish-bar is provided with recesses or pockets 18 to receive the ends of the pins 17, while the base portion of the bar 2 is recessed, as at 19, to clear the spikes 14. The edge of the bar is cut away, as at 20, in order that spikes 21 may engage the bar 2 and pass 80 through the outermost openings 11 of the chair.

From the foregoing description it will be observed that I have devised a novel construction which is strong and durable and 85 fully capable of taking care of the strains exerted upon the rails 3 and 4.

It is obvious that such changes in the details of construction as are permissible by the appended claims may be resorted to without departing from the spirit and scope of the invention. 90

What I claim, and desire to secure by Letters Patent, is—

1. In a rail-joint, the combination with 95 rails having openings formed in the web portions thereof, of a chair adapted to support the ends of said rails, and having a fish-bar embracing said rails, a flange carried by said bar and engaging the heads of said rails, said 100 bar having pockets formed therein, pins extending through the web portions of said rails and engaging in said pockets, a fish-bar spiked to said chair and embracing said rails, said bar having pockets formed therein to receive the opposite ends of said pins, and means housed by said bar and independent thereof to secure said rails to said chair, substantially as described. 105

2. In a rail-joint, the combination with 110 rails having openings formed in their web portions adjacent their ends, of a chair adapted

- to support the ends of said rails, pins extending through the openings of said rails, fish-bars carried by said chair and embracing said rails, said bars having pockets formed there-
in to receive the ends of said pins, means to secure said bars together, and means housed by one of said bars and independent thereof to secure said rails to said chair, substantially as described.
5 3. The combination with rails, of a chair, fish-bars carried by said chair and embracing

said rails, means to secure said bars together, and means housed by one of said bars and independent thereof to secure said rails to said chair, substantially as described. 15

In testimony whereof I affix my signature in the presence of two witnesses.

GABRIEL MURLASITS.
